UNITED STATES PATENT OFFICE.

HENRY B. HIGGINS, JR., OF DENVER, COLORADO.

ATTACHMENT FOR INTERNAL-COMBUSTION ENGINES.

1,376,276.

Specification of Letters Patent. Patented Apr. 26, 1921.

Application filed April 13, 1918. Serial No. 228,322.

To all whom it may concern:

Be it known that I, HENRY B. HIGGINS, Jr., a citizen of the United States of America, residing at Denver, in the county of 5 Denver and State of Colorado, have invented certain new and useful Improvements in Attachments for Internal-Combustion Engines, of which the following is a specification.

10 My invention relates to attachments for internal combustion engines, and particularly to that type providing means for injecting fuel directly into the combustion chamber, at the instants of ignition.

15 It is a well known fact that highly compressed air is the most effective agent yet discovered for thoroughly pulverizing and aerating liquid fuel, thus insuring its reliable ignition and its rapid and complete 20 combustion. However the devices heretofore employed in obtaining the compressed air, in desired proportions and degree of compression, have been complex, both in structure and operation, therefore limiting 25 their use to comparatively large and expensive engines. One of the objects of my invention is to overcome these objections, and to produce a device which is simple and inexpensive in construction and operation. This 30 simplicity also enables the device to operate at higher speeds than the appliances at present in use, and it is adaptable to any style of engine, operating upon any cycle, and using any form of ignition. My device may 35 be arranged to operate automatically, when the degree of compression in the working cylinder rises to a desired point, as disclosed in my co-pending application, Serial No. 228,323 filed April 13, 1918, or it may be 40 mechanically actuated at the proper point in the engine cycle, and the instants of its operation, with respect to the working piston of the engine, may in either case be advanced or retarded to compensate for varying 45 speeds.

Another important object or advantage which it possesses over others is that it supplies air at constant pressure and in uniform quantities, regardless of any variations in 50 the speed of operation, thus eliminating undue wastage of air at low speeds, and insuring thorough pulverization at all speeds.

To accomplish these objects and advantages, I prefer to use a supplemental cylin-

der communicating with the main working 55 cylinder of the engine and with a fuel atomizer of any desired type leading into the combustion chamber adjacent the spark plug or other igniting device, if any be used. This supplemental cylinder is provided with 60 a plunger which is adapted for actuation by the compressed air in the working cylinder, which plunger operates to additionally compress a portion of air taken from the working cylinder, and to eject the same 65 through the atomizer at the proper time.

The drawing which forms a part of this specification is a sectional elevation of the upper portion of the working cylinder of an internal combustion engine equipped with 70 my device.

For the sake of simplicity the engine shown in the drawing is of a two-stroke type, although the device will operate equally as well on any other type. My invention may be readily understood by reference to the accompanying drawings in which I have diagrammatically represented the invention in the complete form which I deem best. 80

Referring specifically to the drawing, 1 indicates the working cylinder of an internal combustion engine, and 2 the working piston therefor. Mounted, preferably above the cylinder 1, and in communication therewith through the port 3, is a supplemental cylinder 4. A differential or step-piston or plunger 5 is mounted for reciprocation in the cylinder 4, said plunger being provided with an enlarged head 6, and a lower reduced portion 7, tapering to engage the inclined seat 8, formed on the casting 9 which houses the cylinder 4. The upper portion of the cylinder 4 is extended beyond the housing 9, and is normally closed by a gland 10 through which extends a rod 11 connected to the plunger 5 and terminating in an enlarged head 12. The gland 10 is apertured at 13, which aperture communicates with a by-pass 14 around the piston, and leading 100 to the lower face of the head 6, thereby maintaining atmospheric pressure in the cylinder above the plunger, and below that portion of the head 6 not exposed to cylinder pressure when the portion 7 is seated. 105

Mounted upon any convenient part of the engine is a standard 15, carrying a rocker arm 16 having a head 17 extending below

and adapted for contact with the head 12 on the rod 11. The arm 16 is pivoted upon said standard 15 and is provided upon the side remote from the head 17 with a friction 5 disk roller 18.

Also mounted on the standard 15, and geared to any convenient rotating part of the motor, as for instance the magneto or valve operating shaft, is a worm 19 which 10 meshes with another worm 20, carried by a shaft 21. Surrounding the worm 20 is a cam 22, adapted to contact the friction roller 18 on the arm 16.

An atomizing element 23 is located above 15 the cylinder 1 and is in communication therewith through the downwardly flaring opening 24. Said element 23 is also in communication with the cylinder 4, through the conduit 25 which leads into the said 20 cylinder 4, and also into the cylinder 1, by means of a branch 26. A ball valve 27 is seated in an enlarged opening in said branch 26 and may be retained in its normal 25 position by a spring 28. The atomizer element 23 also communicates with a source of fuel supply 29 by means of a conduit 30 containing a spring ball valve 31 or equivalent device.

From the foregoing it will be evident 30 that the rise of the piston will cause a pressure to be exerted upon the lower portion 7, of the head 6, upon plunger 5. The pressure caused by the rising piston is likewise communicated to the upper face of the 35 head 6 through the branch 26 and the conduit 25, lifting the ball valve 27 against the retaining spring. The plunger 5 is so proportioned that the area of the top of the head 6 is slightly greater than that of the 40 lower portion 7 thereof, in consequence of which the excess pressure on the top of this head tends to hold it tightly upon the seat 8.

The worms 19 and 20 are so geared, and the cam 22, the arm 16, the head 12 and the 45 roller 18 so proportioned and positioned that, as the piston 2 nears the inner end of its stroke, or about the time of greatest compression, the head 17 contacts the head 12 and lifts the portion 7 off its seat 8. The rise of the plunger 5 closes the upper 50 end of the by-pass 14, and also exposes the whole lower face of the head 6 to the pressure in the cylinder 1. Since the area of the entire lower face of said head 6 is much 55 larger than that of the upper face (the ratio depending upon the degree of pressure desired in the atomizer element 23) the head 6 is forcibly moved upwardly in the cylinder 4, thereby compressing the air in the cylinder above the head. This 60 pressure closes the valve 27, and the compressed air contained in the cylinder passes through the conduit 25 to the atomizer 23 thereby pulverizing the fuel from conduit 30, thoroughly mixing therewith, the heat of com-

pression igniting the fuel, and the mixture is injected into the working cylinder 1 through the flared opening 24, where it combines with the remaining air, and combustion is completed on the outer or working 70 stroke of the piston 2. The working piston performs its functions of exhausting and recharging the cylinder 1, in the usual manner.

During the charging stroke of the cycle, 75 when the pressure in cylinder 1 is below atmosphere, the suction action upon the larger lower face of the head 6 operates to return it to its seat, or springs may be used for this purpose if found desirable. 80

It is to be understood that I have herein described one embodiment of my invention, and means whereby this embodiment may be put into practical operation. It is obvious, however, that other ignition means, 85 such as spark plugs, might be employed; other mechanisms might be utilized for the purpose of giving the initial lift to the plunger 5, and a different atomizing element might be substituted without departing from the broad scope of the invention. It is to be noted that my invention contemplates the introduction to the atomizer of a uniform quantity of highly compressed air, 90 and that this supply is unvaried, constant, 95 and absolutely independent of any variation in the speed of the motor, thereby eliminating any undue wastage of high pressure air at low speeds, and insuring a thorough pulverization. I provide means 100 whereby a charge of air may be taken from the working cylinder and suddenly placed under additional compression, by means actuated by the continued ascent of the working piston, and whereby this charge of 105 compressed air may then be conducted to the atomizing element for pulverization mixture with fuel, and ignition, and thence to the working cylinder, as above set forth.

The scope of this invention is not limited to the mechanisms herein described, as it is obvious that many changes in construction may be covered by the principles involved. Other embodiments may be suggested to those skilled in the art to which the invention pertains, but I desire to secure by Letters Patent all such variations as fall 115 within the scope of the appended claims.

What I claim is:

1. In an internal combustion engine, the 120 combination with a main chamber containing a compressible fluid, means for alternately compressing and expanding said fluid, a supplemental chamber in communication with said main chamber, and adapted 125 to receive a charge of said fluid therefrom, pneumatically operated means in said supplemental chamber actuated by the compression in the main chamber, after receiving an initial movement from a moving part of 130

said engine, to additionally compress said charge, and eject it for utilization in said main chamber, substantially as described.

2. A device of the character described, comprising in combination with a cylinder of an internal combustion engine containing a piston and a compressible fluid, a chamber in communication with said cylinder and adapted to receive a charge of said fluid therefrom in a compressed state, pneumatically operated means in said chamber consisting of a differential piston actuated by the compression in the cylinder upon receiving an initial movement from a moving part 10 of said engine, for additionally compressing said charge, mixing it with combustible matter and ejecting said mixture to the point of ignition, substantially as described.

3. A device of the character described, comprising in combination with a working cylinder and piston of an internal combustion engine, a chamber in communication with said cylinder, said chamber containing a reciprocable plunger, a port leading from 20 said cylinder and opening into said chamber beyond said plunger, an atomizing element, a conduit leading from said chamber and through said element into said cylinder and means for supplying fuel to said element whereby the compression in said cylinder causes a charge of air to enter said chamber through said inlet port, then causes said plunger to operate to additionally compress said charge of air, eject it through said 30 conduit and said atomizing element for the purpose of forming a mixture with the fuel introduced therein for use in said cylinder, upon said plunger receiving an initial movement from a moving part of said engine, 35 substantially as described.

4. A device of the character described comprising, in combination with the working cylinder and piston of an internal combustion engine, a chamber in communication 45 with said cylinder, and a reciprocable plunger in said chamber adapted to be actuated by compression in the cylinder upon receiving an initial movement by the mechanical operation of a moving element of the engine, 50 substantially as described.

5. A device of the character described comprising, in combination with the working cylinder and piston of an internal combustion engine, an atomizing element and

a fuel conduit, a chamber having an opening 55 leading into said cylinder, a plunger reciprocable in said chamber and provided with an outer face adapted to close said opening, a by-pass extending from said cylinder and into said chamber beyond the inner face of the plunger, and communicating with said element and source of fuel, whereby the compression in the cylinder may cause a charge of compressed air to pass from the cylinder to the chamber, be additionally compressed and discharged through said element and adjacent said fuel and into the cylinder, substantially as described.

6. An attachment for internal combustion engines comprising, in combination with the cylinder and piston, an atomizing element and a fuel conduit leading thereinto, a chamber having a port leading into said cylinder and a by-pass opening into said cylinder and into said chamber at a point remote from the cylinder, a piston reciprocable in said chamber between said port and said by-pass entrance, and a conduit leading from said chamber through said element and past the mouth of said fuel conduit, whereby the compression in the cylinder may cause a charge of air to enter the chamber through said by-pass, and subsequently cause a reciprocation of the plunger in said chamber to additionally compress the charge and to thereafter eject it through said element and past the mouth of said fuel conduit, and into said cylinder, substantially as described.

7. An attachment for internal combustion engines provided with a working cylinder and piston, comprising a chamber provided with a plunger having a head adapted to seat upon the end thereof adjacent the cylinder, ports leading from said cylinder to the top and bottom faces of said head, 95 whereby said faces are subjected to the compression in the working cylinder, the exposed area of the top face being greater than that of the bottom face when the head is seated, and less than that of the bottom 100 face when the head is unseated, and means actuated by the engine for initially unseating said head.

In testimony whereof I affix my signature.
